FLUID CONTACT COOKING OF HYDROCARBON OILS

Alfred R. Vander Ploeg, Carroll L. Crawley, and Wiley P. Ballard, Port Arthur, Tex., assignors to Texaco, Inc., a corporation of Delaware

Application December 1, 1954, Serial No. 472,281

4 Claims. (Cl. 208—127)

This invention relates to the cracking and coking of hydrocarbon oils in contact with highly heated powdered or pulverulent coke under fluidized conditions and pertains to a process in which the coke particles are withdrawn from the cracking and coking reactor and subjected to combustion to burn a portion of the coke and hot coke returned to the reactor.

An essential object of the invention is to provide a process capable of continuous operation for extended periods of time. Difficulty has hitherto been experienced in maintaining fluidization during a run. Efforts to operate this type of process have encountered loss in fluidization due to the agglomeration of coke particles with heavy residual hydrocarbon material with resultant plugging of the system and stoppage of the operation. It has now been discovered that a highly critical factor in establishing and maintaining proper fluidization resides in the particular manner of first contacting the oil with the coke particles. The invention provides a method for this contacting and for maintaining efficient fluidized conditions.

In accordance with the invention the oil and coke particles are maintained under fluidized conditions in a reaction zone with the formation of a dense phase and a superposed dilute phase, the oil is introduced into the reaction zone at an intermediate point in the dense phase therein, fluidization is established and maintained by admitting a fluidizing medium, such as steam or light hydrocarbons, into the lower portion of the reaction zone, coke is withdrawn from the dense phase, dispersed with air or oxygen-containing gas and directed through a transfer line to a superposed coke burning zone wherein burning of a portion of the coke is effected under fluidized conditions, highly heated coke is withdrawn from the dense phase of the coke burning zone and is passed by gravity flow downwardly into the dense phase of the reaction zone. This method of procedure enables the proper initial contacting of the coke particles with the oil so as to avoid serious agglomeration and to maintain fluidization in the reaction zone. The oil is preferably introduced into the dense phase of the reaction zone by being discharged therein in a downward direction against the rising vapors and gases which it has been found facilitates the proper dispersion of the oil on the coke particles.

We find that the temperature in the immediate vicinity of the charge nozzle or nozzles, that is, where the oil is first brought into contact with the coke particles is exceedingly critical in maintaining proper fluidization in the reaction zone. In this zone of initial contacting the maximum heat load for heating the charge oil to reactor conditions and for providing at least a portion of the heat of cracking is located. If the heat load becomes excessive coke agglomeration with unvaporized charge will occur as a result of the low temperatures involved and if the condition continues the system will become inoperable. Thermocouples are provided at the zone or zones of the initial contacting and at remote points there-

2

from by means of which the process may be accurately controlled. Thus, for instance, if agglomeration occurs at any point the fact is quickly reflected in a drop in temperature (a temperature differential between the point and the mass of the fluidized bed) and the matter can be remedied before serious agglomeration occurs.

During a run there is a general tendency for the average particle size of the coke to continually increase with a concurrent disappearance of the finer mesh coke. 10 In practicing the invention the coarser coke particles are selectively withdrawn from the reactor-burner cycle so as to thus maintain in the system coke of proper sizes for fluidization. Preferably, this separation is applied to the coke flowing from the coke burner to the reactor and the coarser coke together with agglomerates that may 15 have been formed is withdrawn from the system while the finer coke continues the cycle to the reactor.

The process is adapted particularly for cracking and coking of residual stocks, such as reduced crude petroleum, cracked residues, heavy residues from shale oil, tars from the carbonization of coal and other heavy residues, to produce gasoline as well as gas oil such as is adapted for subsequent catalytic cracking.

For the purpose of more fully disclosing the invention 20 reference is had to the accompanying drawing which is a diagrammatic elevational view of an apparatus constructed in accordance with the invention and constituting an embodiment thereof.

The apparatus includes a reactor or coking drum 10 and a coke burner or separator 11 which is positioned 25 above the reactor or coking chamber. Oil to be subjected to cracking and coking in contact with pulverulent or finely divided coke in the reactor 10 is introduced through a line 12 provided with a plurality of branch lines such as 12a, 12b, and 12c, each having one or more nozzles 13 for distributing the oil into contact with the coke particles in the reactor. Steam or other gas is introduced through a ring distributor 14 at the bottom of the reactor and serves to maintain a fluidized condition of 30 the oil and coke in the reactor.

Coke from the dense phase is withdrawn from the bottom of the reactor 10 and is picked up by means of air or oxygen-containing gas and delivered through line 15 and distributor 15a to the coke burner and separator 11. The line 15 constitutes both a transfer line and a 35 burner. Fluidized conditions are maintained in the chamber 11 and highly heated coke is withdrawn from the lower portion of the chamber and delivered by gravity flow through a standpipe 16 at an intermediate point in the reactor 10 within the dense phase therein. The lines 15 and 16 are of ample diameter, such as for 40 example 24" in a large unit, and are constructed with gentle angles so as to avoid the liability of having either of the lines obstructed by any coke deposits. Flue gas leaves the coke burner 11 through a cyclone or separator 50 17 having a dip leg 18 for returning coke particles to the dense phase therein.

Instead of introducing the charge oil into the reactor at 45 a plurality of different levels therein the oil may be introduced at one level which should be immediately adjacent the outlet of the coke return line 16. But coke is difficult to maintain in a properly fluidized condition. The fluidization characteristics may be improved by increasing the vapor velocity from the reactor but coke carryover 55 from the reactor imposes a limit to this method of improving fluidization. Furthermore, there is always the possibility of depositing too much oil on the coke about the charge entry point with the danger of agglomeration. The method of distributing the charge oil by introducing it 60 at different levels in the fluidized bed is generally a better method of distributing the charge oil and at the same time avoiding coke carryover from the reactor.

The vapors and gases evolved in the reactor 10 are removed through a cyclone or separator 19 positioned in the dilute phase therein and provided with a dip leg 20 extending into the dense phase to return the separated coke particles. The vapors and gases pass out through vapor line 21.

Air or oxygen-containing gas is introduced by a blower 22 and line 23, thence through line 24 into the tubular burner and transfer line 15. An air preheater 25 is provided for starting up but after operating conditions have been established the air preheater is cut out since the temperature of the coke being removed from the reactor is adequate to initiate burning in the transfer line 15.

In the fluid contact coking process there is a tendency as the run proceeds for the build-up in the system of coke particles of increased size. The enlarged particles interfere with proper fluidization and may cause agglomeration and plugging of the system. Accordingly, a portion of the coke is regularly withdrawn from the cycle, preferably at a point downstream from the coke burner, and this coke is subjected to classification to segregate the larger sized coke particles from the finer coke and the larger sized coke is removed from the system. This separation may be accomplished in various ways such as by screening, centrifugal classifying and gaseous elutriation. A shown in the drawing a portion of the coke flowing in line 16, only a minor portion required, is withdrawn and conducted by a line 26 to an elutriator 27. Steam or other gaseous medium admitted through a distributor 28 fluidizes the coke particles in the chamber 27 with the resultant formation of a dense phase and a dilute phase therein. The coarser particles are concentrated in the dense phase and are removed by a line 29 from the system to constitute the product coke of the process. The finer coke particles are removed in the steam or other gases and are conducted by a line 30 to the reactor 10 preferably entering the reactor through the conduit 16. Thus the larger sized coke which might interfere with proper fluidization is selectively withdrawn from the system.

By initially contacting the oil with the coke particles in the reactor at an intermediate point in the dense phase of the fluidized mass so as to avoid agglomeration and provide good fluidizing conditions and then by selectively removing during the run any coke particles of too large a size for good fluidization a condition of effectual fluidization is continuously maintained in the reactor.

A coke hopper 31 is provided for storing coke between runs and for furnishing make-up coke when required. At the end of a run the coke in the system is removed to the hopper through unloading lines (not shown) and at the beginning of the run coke from the hopper is blown to the coke burning chamber through a loading line (not shown). Normally, there is sufficient fine coke in the system for the desired contacting and fluidizing in the reactor but at times the amount of coarser coke removed from the system may increase so as to require the addition of make-up coke. This may be accomplished by withdrawing coke from the hopper 31 and slurring it with a liquid, preferably oil. Thus oil is introduced by a pump 32 through a line 33 picking up coke from the hopper and directing it to the reactor preferably at a lower point therein. It sometimes happens that when the make-up coke is admitted to the system as a dry powder there is a considerable tendency for this coke to be carried out of the system; by introducing the coke wetted with the oil this loss in coke is avoided.

The vapor line 21 from the reactor 10 extends to a fractionating tower 34 for fractionating the reaction products delivered from the reactor. The overhead vapors from the tower 34 pass through a vapor line 35 to a condenser and distillate receiver (not shown). The charging stock or a portion thereof is introduced through a line 36 into the vapor line 21 to provide cooling and to prevent coking in the vapor line. The mixture of charging stock and effluent vapors and gases from the reactor flow into the

lower portion of the fractionator 34. Unvaporized charge stock together with heavy reflux condensate is withdrawn from the bottom of tower 34 and is directed by a pump 37 through the line 12 to the reactor. In some cases a portion of the charging stock may be directed to the lower portion of the fractionator 34 although generally it is found that all of the charging stock may well be introduced through the vapor line.

Steam is a good fluidizing medium for the process. Light hydrocarbons including normally gaseous hydrocarbons as well as the lighter liquid hydrocarbons are also satisfactory and at times may be more economical than steam. Thus selected portions of the lighter hydrocarbons produced in the process, such as propane and butane fractions and naphtha, may be recycled for promoting fluidization in the reactor. In one method of operation effluent from the reactor 10 is recycled to the reactor. In such operation the vaporous stream is preferably subjected to partial cooling to separate the higher boiling components and the vaporous constituents are recycled by a compressor or blower. These various methods of recycling fractions of the reactor effluent are used to supplant, or preferably merely to reduce, steam requirements.

When good fluidizing conditions are being maintained in the reactor the temperature is fairly uniform throughout the fluidized mass. Thus, for example, when operating within a range of 975-1000° F. as indicated by a thermocouple located near the outlet of the charge nozzle the temperature shown by a thermocouple positioned at a more remote point in the fluidized mass will normally be within about 5° F. of the temperature of the first thermocouple. A spread of about 10-15° F. between these two temperatures indicates that agglomeration about the charge nozzle is beginning to occur. By observing the temperatures between points adjacent the charge nozzles and at remote points in the fluidized mass it is possible to quickly observe any tendency toward agglomeration so that the condition may be remedied before it gets serious. The condition may be corrected by various means; the temperature may be raised by increasing the temperature in the coke burner, the steam partial pressure in the reactor may be increased, steam may be introduced into the oil charge line or injected about the charge nozzle. Thus by getting a timely warning by means of the temperature differential any tendency toward agglomeration may be checked and conditions of good fluidization maintained.

The temperature in the reactor will generally be of the order of 900° F. and 1000° F. Velocities and rates of flow and other conditions will vary considerably with the size of the equipment and with other factors. In a typical operation the temperature in the reactor is 975° F. under 10 p.s.i.g. pressure with a coke to oil ratio of about 10:1. Reduced crude of 16 API gravity is charged to the vapor line 21 at a rate of 125 bbls./hr. reducing the temperature therein to 825° F. With a pressure of 7 p.s.i.g. in the fractionator 34 and a temperature of 800° F. at the bottom the oil is delivered by pump 37 to the reactor at a temperature of 780° F. Steam is admitted to the reactor at a rate of 6,300 lbs./hr. With a hold-up in the system of 58.9 tons of coke, coarse coke is removed from the system through line 29 at a rate of 1.47 tons/hr. The temperature in the coke burner is 1075° F. under a pressure of 7 p.s.i.g.

In a modification of the process different types of charging stock may be admitted into different points in the reactor and the lighter or more refractory stocks admitted into the lower portion of the dense phase and the heavier stocks admitted at a higher point. Thus, for example heavy virgin stocks such as reduced crude may be admitted into an upper portion of the dense phase bed and recycle gas oil admitted into a lower portion.

Obviously, many modifications and variations of the invention, as hereinbefore set forth, may be made without departing from the spirit and scope thereof, and

therefore only such limitations should be imposed as are indicated in the appended claims.

We claim:

1. A continuous process for the cracking and coking of a heavy hydrocarbon oil that comprises subjecting said oil to contact with coke particles in a dense phase fluidized bed reaction zone maintained at a temperature within the range of about 900 to 1000° F., introducing said oil at an intermediate level in said reaction zone whereby said oil is distributed over the coke particles therein, introducing a fluidizing medium comprising steam into said reaction zone, withdrawing coke from said reaction zone and subjecting said withdrawn coke to combustion, recycling resultant highly heated coke to said reaction zone, determining the temperature at a first point adjacent to the point at which said oil is introduced into said reaction zone, determining the temperature at a second point within said reaction zone at a point remote from said first point whereby conditions preventing agglomeration prevail so long as the temperature of said first and second points are substantially the same, and increasing the temperature of said reaction zone within said range of about 900 to 1000° F. responsive to a temperature differential between said first and said second points in excess of 10° F. thereby maintaining conditions preventing agglomeration.

2. The process of claim 1 wherein said reaction zone temperature and the ratio of steam to oil in said reaction zone are increased responsive to a temperature differential between said first and said second points in excess of 10° F.

3. The process of claim 1 wherein said reaction zone temperature is increased and steam is introduced with said oil responsive to a temperature differential between said first and said second points in excess of 10° F.

10 4. The process of claim 1 wherein said reaction zone temperature is increased and steam is injected about the oil inlet point responsive to a temperature differential between said first and said second points in excess of 10° F.
